US00D986277S

(12) **United States Design Patent** (10) **Patent No.:** **US D986,277 S**
Grossberg (45) **Date of Patent:** **** May 16, 2023**

(54) **DISPLAY SCREEN OR PORTION THEREOF WITH GRAPHICAL USER INTERFACE**

(71) Applicant: **Lombart Brothers, Inc.**, Jacksonville, FL (US)

(72) Inventor: **Matthew Grossberg**, Atlantic Beach, FL (US)

(73) Assignee: **Lombart Brothers, Inc.**, Jacksonville, FL (US)

(**) Term: **15 Years**

(21) Appl. No.: **29/767,498**

(22) Filed: **Jan. 22, 2021**

Related U.S. Application Data

(63) Continuation of application No. 29/706,037, filed on Sep. 17, 2019, now Pat. No. Des. 938,485.

(57) **CLAIM**

I claim the ornamental design for a display screen or portion thereof with graphical user interface, as shown and described.

DESCRIPTION

The sole FIGURE is a front view of the claimed design of a display screen or portion thereof with a graphical user interface.

The outermost broken lines in the FIGURE illustrate a display screen or portion thereof and form no part of the claimed design. The other broken lines in the FIGURE illustrate portions of the graphical user interface that form no part of the claimed design.

1 Claim, 1 Drawing Sheet
